Inventor
D. A. Manuel,
by his Esq. E. F. Brown,
Atty.

DAVID A. MANUEL, OF NAPA CITY, CALIFORNIA.

Letters Patent No. 85,746, dated January 12, 1869.

IMPROVEMENT IN PLOWS.

The Schedule referred to in these Letters Patent and making part of the same.

To all whom it may concern:

Be it known that I, DAVID A. MANUEL, of Napa city, in the county of Napa, and State of California, have invented new and useful Improvements in Plows; and I do hereby declare that the following is a full and exact description of the same, reference being had to the accompanying drawings, and to the letters of reference marked thereon, of which—

Figure 1 is a side view, showing the landside, and Figure 2, a top view.

This invention is an improvement upon the plow patented to D. A. Manuel, May 5, 1868, and consists in a simple form of mould-board, and a more substantial and conveniently-operating device, for reversing said mould-board.

To this end, the mould-board is made in one piece, of cast-iron or steel, in the form represented in fig. 2.

The landside and standard are also made in one piece, in the form represented in fig. 1, a simple arm uniting the mould-board to the landside, and a simple lever serving to lock the mould-board in position, on either side of the landside.

In the drawings—

A represents the mould-board, which is made in a nearly diamond-form, with edges *a a* quite straight, but edges *a' a'* slightly concave.

This board is, on its rear side, and by means of strong bolts or rivets, *b b*, fastened firmly to a stout arm, C, which is pivoted, as shown at *c*, to the rear edge of the standard, or vertically-projecting part, D', of the landside D.

The landside is a strong piece of cast-iron, provided, near its centre, with the vertical projection aforesaid, for the purpose of supporting the mould-board and plow-beam, and having a slot, *s*, extending down through it, in front of the projection, and another, *s'*, running from its front end into the slot *s*.

E is a lever, with its handle extending above the plow-beam, and pivoted at *e*, below which point it is attached to a sliding lock-bolt, *e'*.

The forward end of the landside is made in the angular or cuneiform shape, shown at *m* in fig. 1, and the landside-edge of the mould-board is provided with a downward-projecting flange, *i*, at each end, formed to fit accurately over the end *m* of the landside, so as to form a close joint, and so that when in the positions shown in figs. 1 or 2, the side of the mould-board at *r*, and the side of the landside, shall together form a straight line. The flange *i* is thin at the point of contact with the end of the landside, and when the mould-

board is in the position last referred to, the bolt *e'* can be forced behind the edge of the flange so as to firmly lock the mould-board to the landside by simply throwing the handle of the lever back.

The wedge-shaped end of the landside, entering into the wedge-shaped notch in the rear end of the flange *i*, prevents the plow-point *t* from having any vertical motion, while the bolt *e'* and the landside prevent it from having any lateral motion when locked.

The mould-board can be turned on the pivot *c*, so as to throw it on either side of the landside, and can be locked by the device above described equally well in either position.

The form of the mould-board is such that the dimensions, contour, &c., of the plow are the same in either case, the only difference being that in the one case it is a left-hand, and in the other a right-hand plow.

The device is exceedingly simple, strong, and durable, and can be made at a cost not exceeding, or very slightly exceeding, that of the common single mould-board plow. There is nothing about it liable to clog or foul in any way, or to get out of working-order in any kind of soil.

Having thus fully described my invention,

What I claim, and desire to secure by Letters Patent of the United States, is—

1. The landside D, when provided with the vertical projection D', the pivot *c*, the slots *s s'*, and the wedge-shaped extremity, all arranged and constructed in a simple piece of cast-metal, substantially as described, and for the purposes set forth.

2. The mould-board A, when constructed in the shape described and shown, pivoted, at its middle, to the rear edge of the landside by an arm, C, operating as described, and provided with the flanges *i i*, arranged under the landside-edge at the ends, all constructed and operating in combination with the landside above described, substantially as and for the purposes specified.

3. The combination of the landside and mould-board, above described, with the lever E, pivoted at *e*, and connected with a sliding lock-bolt *e'*, arranged inside of the landside in a slot or chamber prepared for the purpose, substantially as described, and for the purposes set forth.

DAVID A. MANUEL.
